Inventor,

E. S. Bennett

ERASTUS S. BENNETT, OF NEW YORK, N. Y., ASSIGNOR TO HIMSELF AND JUSTUS SMITH.

Letters Patent No. 86,125, dated January 26, 1869; antedated January 13, 1869.

IMPROVEMENT IN LOW-WATER DETECTORS FOR STEAM-BOILERS.

The Schedule referred to in these Letters Patent and making part of the same.

To all whom it may concern:

Be it known that I, ERASTUS S. BENNETT, of the city, county, and State of New York, have invented a new and improved Low-Water Detector for Steam-Boilers; and I do hereby declare that the following is a full and exact description thereof, reference being had to the accompanying drawing, and to the letters of reference marked thereon.

The nature of my invention consists in the construction of the valve and its case, and in the arrangement of the floats, so as to secure perfectly reliable and at the same time simple and cheap detectors, (or alarms,) which may be applied to any style of boiler now in use without removing the man-hole plate, and which can be kept well oiled without trouble.

Also in arranging the valve-case, so that the valve-packing may be easily tightened without removing the detector from the boiler.

To enable others skilled in the art to make and use my invention, I will proceed to describe its construction and operation.

In the drawing—

Figure No. 1 represents a sectional view of my detector, with the whistle I attached.

x x, a cylinder.

A, its cap.

B, piston.

C, packing.

D, pipe, leading to whistle, as shown, (or to the ordinary signal-whistle above its valve.)

E, a hollow rod, closed at its lower end and at *p*.
F, opening in pipe.

H, flange, the lower side of which is screwed into the boiler, and into the upper side of which the cylinder is fastened.

This flange furnishes the valve-stem E with a guide at S, and is perforated with two or more holes at G.

J is a float, fastened to the lower end of the rod.

K is a float, with a tube through its centre, by means of which it may slide on the rod. This float is partially filled, or made heavy enough to sink about two-thirds in the water.

The steam has access through the holes G and F (and also through the piston by the holes described by dotted lines) to the upper side of the piston.

The float J is always under water, and keeps the piston crowded up against the stop-pin N.

The heavy sliding float follows the water down, until by resting on the lower float J, it opens the valve, and steam escapes to the whistle.

Figure No. 2, a bottom view of the flange.

Figure No. 3, a top or bottom of float K.

What I claim as my invention, and desire to secure by Letters Patent, is—

The arrangement of floats K and J, hollow rod E, and balance-valve C, substantially as described.

E. S. BENNETT.
